UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

KILN BOTTOM.

Application filed August 13, 1925. Serial No. 49,999.

My present invention relates to kilns, and more particularly to an improved kiln bottom.

In building kilns for the burning of brick, there is an excessive loss in the arches thereof, both of the brick which form the arches and of the heat which is prevented from properly flowing through the arches into the kiln itself. Kiln bottoms as at present made are generally built up of brick work, either by burning arches or by jetting over with the result that the area of the openings through the arches has not been sufficiently large to allow the heat to travel from the fire box into the kiln proper. The result is that the bricks forming the arch are overburned while there is a great loss of heat due to the constricted area of opening through the arch which blocks the flow of heat from the fire box. In my present invention I have worked out a means for obviating the objections existing in prior structures and have devised a kiln bottom which can be cheaply built and easily repaired. Preferably this kiln bottom is made up of a plurality of pre-cast refractory concrete shapes, although pre-cast shapes of any other suitable material may be utilized if desired. With the pre-cast shapes of my present invention, a kiln bottom may be quickly and economically built up and the area of the openings therethrough may, in the aggregate, be any desired and bear any relation to the area of the fire box opening that is desired, and in the practical embodiment of my invention, I have secured an area of opening through the pre-cast block kiln bottom that is over twice the area of the fire box opening and, as compared with the aggregate opening between the bricks of prior structures, is over three times as large. As my present invention is applicable to the building of a kiln bottom where mechanical building of the kiln is employed, and where, in such mechanical building, it is customary to utilize what is known in the art as "finger courses", I have utilized as an entirely new feature the finger spaces between the finger courses of the unit as traversing flues in order to obtain a more uniform distribution of the heat passing through the bottom of the kiln.

The principal object of my invention, therefore, is an improved and novel kiln bottom.

Another object of my invention is an improved pre-cast refractory shape adapted to be utilized as an element in a built up kiln bottom.

A further object of my invention is the utilization of the finger spaces in the lower courses of the brick in the kiln in combination with an improved pre-cast kiln bottom for obtaining a more uniform flow of heat from the fire box into the kiln.

Other objects and novel features of the combination and arrangement of parts comprising my invention will appear as the description of the invention progresses.

In the accompanying drawings illustrating a preferred embodiment of my invention,

Fig. 1 is a front elevation of a portion of a kiln structure;

Fig. 2 is a sectional side elevation on the line 2—2 of Fig. 1 and showing, in addition, the units of bricks arranged thereon, and

Fig. 3 is a perspective view of one unit of the pre-cast kiln bottom.

Referring to the drawings, 10 designates the brick, preferably fire brick, built up in piles, as shown, each pile being separated from the other a distance sufficient to define a fire box or chamber 11. Numeral 12 designates a block, preferably of pre-cast refractory concrete—although any other suitable material may be employed—such block 12 having an arched cut-away portion 13 at one end, such arched portion being equal in extent to approximately one half the width of the fire box 11 so that, when two of the blocks 12 are placed in position, as shown in Fig. 1, the adjacent and cooperating arch portions 13 will be semi-circular in form and with the center thereof in the medial vertical line of the fire box 11. Each of the blocks 12 is provided on one face thereof at the top of the arch portion 13 with a laterally projecting portion 14, such blocks also being provided on the same face, but at the other end of the block, top and bottom, with lateral projections 15. The projections 15 extend outwardly as far as the projection 14, and such projections 15 are arranged parallel to each other to define therebetween a trough or passage 16. The blocks 12 are built up on top of the piles of bricks 10 as illustrated in Figs. 1 and 2 and, referring to

such figures, it will be obvious that heated gases from fires in the fire boxes 11 will pass up between adjacent blocks 12 into the kiln built thereon and will also pass between adjacent blocks 12 in a horizontal direction through the passages 16. In the usual size kiln the area of the opening of the fire box 11 is ordinarily and usually 412 square inches, approximately. Utilizing a kiln bottom built according to my present invention, the area of the openings between adjacent blocks 12 comprising the kiln bottom is approximately 970 square inches, from which it will be obvious that the area for the passage of heated gases through the kiln bottom from the fire box is more than twice that of the opening of the fire box or fire arch itself, and this area, approximately 970 square inches, is approximately three times the area of the openings between the bricks forming the top of kiln bottoms heretofore employed.

Referring now to Fig. 2 wherein is shown a unit of brick 17 on top of the kiln bottom 12, and which units are assumed to be built into the kiln by mechanical means, there is shown for such purpose the so-called finger courses 18, the spaces 19 between finger courses being provided for the passage of the brick lifting fingers of the mechanical lifting device. By properly positioning the finger spaces 19 vertically over the space between adjacent blocks 12—such spaces, of course, being formed between adjacent blocks 12 by the lateral projections 14 and 15—there is provided a plurality of relatively large passages over the openings in

the kiln bottom and through which the heated gases may readily flow upward through the brick forming the unit 17. 40

While I have described the units forming my improved pre-cast kiln bottom shape of a particular form and contour, yet it is obvious that I may vary this form or contour, as well as the material of which it is built, within relatively wide limits without departing from the spirit of the invention. I do not, therefore, wish to be limited in the interpretation of my invention other than as pointed out particularly in the appended claims. 45 50

Having thus described my invention, what I claim as new is:

1. An improved unit for building a kiln bottom, comprising a substantially rectangular form of pre-cast refractory material, such form having a substantially arched portion at one end and a plurality of laterally extending projections on one face thereof. 55 60

2. An improved kiln bottom comprised of a plurality of pre-cast refractory material shapes, each having an arched portion at one end and a plurality of lateral projections on one face thereof, such shapes being arranged in pairs and each pair being arranged parallel to the next succeeding pair and over the fire box or arch of a kiln whereby a plurality of parallelly arranged and vertical passages are provided through the bottom. 65 70

In testimony whereof, I have signed my name to this specification.

CLAUD E. FULLER.
